United States Patent Office

Des. 210,559

Patented Mar. 19, 1968

210,559

BOX CAMERA

Pasquale A. Mercorelli, 37 Halleck St.,
Newark, N.J. 07104

Filed May 24, 1967, Ser. No. 7,257

Term of patent 14 years

(Cl. D61—1)

FIG. 1

FIG. 2

FIG. 3

FIG. 4

FIG. 5

FIG. 6

The broken line showing of a representative flash attachment in FIGURE 1 is for illustrative purposes only.

I claim:

The ornamental design for a box camera, as shown and described.
